UNITED STATES PATENT OFFICE.

JOSEPH B. WIEGEL, OF MAGNOLIA, MINNESOTA.

HOOD FASTENER AND LOCK.

1,171,911.

Specification of Letters Patent. Patented Feb. 15, 1916.

Application filed June 12, 1914. Serial No. 844,714.

To all whom it may concern:

Be it known that I, JOSEPH B. WIEGEL, a citizen of the United States, residing at Magnolia, in the county of Rock and State of Minnesota, have invented certain new and useful Improvements in Hood Fasteners and Locks, of which the following is a specification.

My invention relates to fasteners and locks 10 and more particularly to a hood fastener and lock for an automobile.

The primary object of my invention resides in the provision of a movably mounted casing having means associated therewith 15 for detachably securing the same, the casing having means mounted therein and associated with the securing means for securely locking the casing in position.

Another object of my invention resides in 20 the provision of a novel means mounted in the casing and associated with the locking mechanism for controlling the locking mechanism and further provides an improved means for operating the locking mechanism, 25 the operating means being removably associated with the casing.

A further object of my invention resides in 30 the provision of an improved resilient means for mounting the casing, the latter being preferably carried by the frame of the vehicle.

A still further object of my invention resides in the provision of a novel means carried by the hood for receiving the casing, 35 the latter having novel means associated therewith for facilitating the removal of the casing from the securing means.

A still further object of my invention resides in the provision of a device of the character described that is simple in construction, 40 efficient in operation and one that can be manufactured and placed on the market at a minimum cost.

Other objects as well as the nature, character 45 and scope of my invention will be more readily understood from the following description taken in connection with the accompanying drawings and pointed out in the claims forming a part of this specification.

Referring to the drawings: Figure 1 is a front elevational view of my invention, the dotted lines showing the position which the casing assumes when being removed; Fig. 2 55 is a side elevational view of my invention in locked position, the dotted lines showing

the casing in and out of engagement with the securing means; Fig. 3 is a front elevational view of my invention partly in section showing especially the locking mechanism within 60 the cylinder, and the construction of the resilient or elastic connection between the casing and the frame; Fig. 4 is a vertical sectional view taken on the line 4—4 of Fig. 3 in the direction which the arrow points; Fig. 5 is a top plan view of the anchor plate; Fig. 6 is a perspective view of the key for operating the locking mechanism.

Referring more particularly to the drawings in which similar reference numerals 70 designate corresponding parts throughout the different views, I provide an anchor plate 1, the latter being secured to the frame 2 of the vehicle by suitable fastening devices 3 and further provided on the raised portion thereof with a transverse slot 4. Disposed upon the raised portion of the plate about the slot 4 is a cylinder 5, the upper end of which is open and in which cylinder is slidably mounted a piston head 6, the latter 80 having a rod 7 extending therefrom through an opening 8 in the bottom of the cylinder and through the slot 3 into the interior of the raised portion. A coil spring 9 is disposed about the rod between the head 6 and the 85 bottom of the cylinder for a purpose to be hereinafter described. In order to hold the free end of the rod within the raised portion of the plate, I have disposed a washer 10 about the same, the washer bearing 90 against the under surface of the raised portion about the slot 4 and prevented from downward movement on the rod by means of a pin 11 extending transversely through the rod and arranged in close relation therewith. 95 The upper end of the cylinder is threaded as at 12 and is arranged in threaded engagement with the tapering projection 14 formed on the lower end of the casing 15, the upper end of which casing has a pair of oppositely disposed trunnions 16 extending laterally from the sides thereof, the trunnions being 100 removably engaged in the vertically arranged recesses 17 in the upper ends of the supporting bars 18 secured in spaced parallel relation to the outer sides of the hood 19 by means of suitable fastening devices 20. By this arrangement the recesses will prevent lateral and transverse movement of the casing with respect to the hub and because 110 of this arrangement the efficient operation of the locking mechanism is facilitated. For

the purpose of facilitating the removal of the trunnions 16 from the recesses 17, I have provided the upper outer edge of the casing 15 with a finger piece 21.

5 In order to securely lock the casing and prevent the surreptitious removal of the same, I have extended partitions 22 from the opposite sides and formed substantially intermediate the ends of the rectangular 10 casing 15 and have arranged the outer ends of the partitions in spaced parallel relation and have further slidably mounted on the same a bolt 23, one end of which is reduced and rounded and arranged for engagement 15 with the circular opening 24 in the side of the casing and is further arranged in alignment for engagement, at times, with a transversely extending recess in the inner side of one of the bars 18. In order to guide the 20 bolt and prevent the same from having unnecessary movement, I have disposed a leaf spring 26 on the upper surface thereof, the latter bearing against the projection 27 within the casing. A coil spring 28 is disposed between the inner end of the bolt and one side of the casing for facilitating the 25 sliding movement of the casing. In order to actuate the bolt 23, I provide a key 29 and arrange the same, at times, in the key 30 hole 31 in the plate 31, the latter being removably secured in the casing by means of suitable fastening devices 32. The key is engaged in the notch 33 provided on the under surface of the bolt. The key is easily 35 rotated and is in no way interfered with by the partitions 22 which are suitably spaced as above stated. For the purpose of controlling the movement of the bolt 23, I have provided a pin 34 and extended the same 40 longitudinally through the upper part of the casing and arranged the same for engagement, at times with a recess 35 formed upon the top surface of the bolt. It can be easily seen that when the key 39 is rotated and engaged in the notch 33, the bolt will be forced 45 rearwardly, whereupon the pin 34 will engage the recess 35 and prevent the outward movement of the bolt, until desired.

The operation of my invention is as follows: Assuming that the trunnions 15 are 50 out of engagement with the recesses 17 and it is desired to lock the hood to the frame, the finger piece 21 is engaged by one hand of the user (not shown) and lifted against the 55 tension of the coil spring 9 within the cylinder until the trunnions are in a position above the upper ends of the bars whereupon they are placed in alignment with the recesses 17 and released, thus securing the hood 60 to the frame. The pin 34 is now lifted upwardly out of engagement with the recess 35 in the top of the bolt whereupon the coil spring 28 will shove the bolt through the opening 24 and into the recess 25 in one of 65 the supporting bars 18, the bolt being guided

during its movement by means of the leaf spring 26 positioned within the casing, thus securely locking the hood to the frame. When it is desired to remove the bolt 23 from engagement with the recess 25, the key 70 29 is inserted in the key hole 30 and rotated until the inner end of the key is engaged in the notch 33 whereupon the bolt will be slid inwardly and when in alignment with the pin 34, the latter will drop due to the 75 weight on the upper end of the same and automatically lock the bolt within the casing. In order to remove the trunnions 16 from engagement with the recess, all that is necessary is to lift the same by means of the 80 finger piece until they are above the plane of the upper ends of the bars 18 and pull the same outwardly.

Although I have shown and described the preferred form of my invention, I desire it 85 to be understood that I am not limited to the exact details shown, however, I desire that great stress be laid upon the arrangement of the movably mounted casing, the latter having locking means mounted therein 90 and associated with the securing means for the casing, for securely locking the casing.

From the above description taken in connection with the accompanying drawings, it can easily be seen that I have provided a 95 device that is simple in construction containing but a few simple parts that can be cheaply manufactured and assembled and when assembled can be placed upon the market and sold at a minimum cost.

It will be understood that the above description and accompanying drawings comprehend only the general and preferred embodiment of my invention and various minor changes in detail of construction, proportion and arrangement of the parts may be made within the scope of the appended 105 claims and without sacrificing any of the advantages of my invention.

Having thus fully described my invention, what I claim as new and desire to secure by Letters Patent, is:—

1. A fastener and lock including a movably and resiliently mounted casing, engaging means projecting from the upper end of the casing, securing means for receiving the engaging means, said securing means preventing movement of the casing, and locking mechanism disposed within the casing and associated with the securing means for preventing surreptitious removal of the casing.

2. A fastener and lock including a movably and resiliently mounted casing, trunnions projecting from the upper sides of said casing, a pair of supporting bars provided with recesses in their upper ends for receiving said trunnions, and locking mechanism disposed within the casing and associated with one of the supporting bars for

preventing surreptitious movement of the casing.

3. A fastener and lock including an anchor plate provided with a slot, a cylinder disposed upon the plate, a rod extending through the cylinder and connected to the plate, a coil spring disposed about the rod, a head formed on the upper end of the rod for engagement with said spring, a casing secured to the upper end of the cylinder, means for detachably securing the upper end of the casing, said securing means preventing movement of the casing, and locking mechanism disposed within the casing and associated with the securing means for preventing the surreptitious removal of the casing.

4. A fastener and lock comprising an anchor plate provided with a slot, a cylinder disposed upon the plate, a rod extending through the cylinder and connected to the plate, a spring disposed about the rod, a head on the upper end of the rod for engagement with said spring, a casing secured to the upper end of the cylinder, trunnions extending from the opposite side of said casing, a pair of supporting bars provided with recesses in their upper ends for receiving said trunnions, and locking mechanism in said casing for removable engagement with one of the supporting bars for preventing the surreptitious removal of the casing.

5. A fastener and lock comprising an anchor plate provided with a slot, a cylinder disposed upon the plate, a rod extending through the cylinder and connected to the plate, a spring disposed about the rod, a

head on the upper end of the rod for engagement with said spring, a casing secured to the upper end of the cylinder, trunnions extending from the opposite side of said casing, a pair of supporting bars provided with recesses in their upper ends for receiving said trunnions, a bolt slidably and resiliently mounted in the casing for removable engagement with one of said supporting bars, means for operating the bolt, and means for controlling the operation of the bolt.

6. A fastener and lock comprising an anchor plate provided with a slot, a cylinder disposed upon the plate, a rod extending through the plate and connected to the plate, a spring disposed about the rod, a head on the upper end of the rod for engagement with the said spring, a casing secured to the upper end of the cylinder, engaging means on the casing, supporting means for receiving the engaging means for preventing accidental movement of the casing, a bolt slidably and resiliently mounted in the casing for removable engagement with the supporting means, said bolt provided with a recess, means for operating the bolt, and a pin slidably mounted in the casing for engagement with the recess in the bolt for removably holding the bolt out of engagement with the supporting means.

In testimony whereof I affix my signature in presence of two witnesses.

JOSEPH B. WIEGEL.
